UNITED STATES PATENT OFFICE.

UTAKICHI KAWASAKI, OF SAN FRANCISCO, CALIFORNIA.

BOTTLE CLOSURE.

Application filed June 23, 1920. Serial No. 391,051.

To all whom it may concern:

Be it known that I, UTAKICHI KAWASAKI, a subject of the Emperor of Japan, residing at San Francisco, in the county of San Francisco and State of California, have invented new and useful Improvements in Bottle Closures, of which the following is a specification.

This invention relates to improvements in closures for bottles, jars, and the like, particularly milk bottles.

The primary object of this invention is to provide a simple and inexpensive closure which is constructed so that it may be opened without being removed from the bottle or necessitating the disruption or tearing of the closure, said closure being formed of rubber or some other similar material and arranged so that when pressure is applied thereto with the fingers of the hand the closure will open on one side and upon release of pressure will spring back into closed position and seal the bottle.

A further object of the invention is to provide a closure which may be operated to open and seal a bottle or the like without necessitating touching the mouth of the bottle with the fingers of the hands, whereby a highly sanitary closure is provided.

The invention possesses other advantages and features, some of which, with the foregoing, will be set forth at length in the following description wherein I shall outline in full that form of the invention which I have selected for illustration in the drawings accompanying and forming a part of the present specification. In said drawings, I have shown one form of the construction of my invention, but it is to be understood that I do not limit myself to such form, since the invention as expressed in the claims may be embodied in a plurality of forms.

Figure 1 is a perspective view of a bottle with my improved closure mounted thereon and showing the closure held open.

Figure 2 is a vertical sectional view taken through the closure showing the closure as when sealing the bottle.

Figure 3 is a front elevation of the closure.

Figure 4 is a top plan view of the closure showing it applied to a bottle.

In the present embodiment of the inven-

tion the closure is in the form of a flanged 55 cap formed of one piece of rubber or other similar material and consists of a body 1 having a depending flange 2. The closure is adapted to fit snugly over the mouth 3 of a bottle or like container 4 as shown in 60 Figure 2 of the drawings.

To facilitate opening the bottle the closure is provided with a segmental opening 5 in one side of the flange 2. The lower edge of the flange and the edge of the opening 5 are bordered by integral beads 6 and 7 which are thicker than the rest of the closure and strengthen the closure as a whole.

The opening 5 is disposed so that the body or top of the closure on one side thereof 70 lies on the top only of the mouth 3 for a distance equal to the length of the opening and closely engages with said mouth so as to provide an effective sealing of the bottle.

To open the bottle with the closure applied thereto as shown in Figure 2, pressure is applied to the top or body 1 of the closure by pressing with the finger downwardly and inwardly from the upper edge of the opening 5 as shown in Figure 1. This 80 stretches the opening 5 so that said opening registers with the open mouth of the bottle as shown in Figure 1 and opens the mouth sufficiently to permit the contents of the bottle to be poured therefrom. As soon 85 as the pressure from the fingers is released the body being of rubber will spring back into position as shown in Figure 2 and seal the bottle. By having the lower edge of the flange 2 and edge of the opening 5 provided with the beads 6 and 7, these portions are less elastic than the other portions of the closure and will snugly embrace the bottle where contacted therewith so that a 90 tight seal is insured.

The invention consists in the provision of an elastic closure for bottles, jars and the like receptacles, wherein the closure is constructed so that by stretching the material thereof at a certain point said closure will 100 open sufficiently to permit the contents of the bottle to be removed therefrom and upon release of the pressure said closure will quickly spring back into sealing position.

I claim:—

1. A closure for bottles comprising a flanged one-piece cover formed of elastic material and provided with an imperforate

105

top and a discharge opening formed in the flange thereof, said opening being brought into position to provide for discharge of the contents of a bottle by stretching the 5 cover.

2. A closure for bottles comprising an elastic body adapted to embrace and seal the mouth of a bottle and having an opening therein normally disposing out of registration with the mouth of the bottle and 10 lying in a position to one side of the opening in the bottle and which is brought into

registration with the mouth of the bottle by stretching said body.

3. A closure for bottles comprising an 15 elastic body having an imperforate part adapted to extend over the mouth of a bottle and a perforate part normally disposed in a position out of registration with and to one side of the mouth, the construction being such that said perforate side is brought into registration with the mouth of the bottle by stretching the imperforate portion. 20

UTAKICHI KAWASAKI.
